4 Claims. (Cl. 46—40)

This invention relates to toys and more specifically to a novel and improved toy loader for simulating the loading of a truck trailer or other object on and removal from a cooperating transporting vehicle.

One object of the invention resides in the provision of a novel and improved platform and loading mechanism for loading and unloading toy motor vehicles and trailers onto an improved toy flat car of the type utilized in model railway equipment.

Another object of the invention resides in a novel and improved lift mechanism for vehicles, trailers and the like.

A still further object of the invention resides in the novel and improved toy automotive vehicle and cooperating railroad flat car adapted to receive and support said vehicle.

A further object of the invention resides in the provision of an improved toy trailer of the type adapted to be transported by a motor driven tractor.

A still further object of the invention resides in the provision of a novel and improved toy having a high degree of play value and adapted to simulate the loading of trailers on railroad cars.

The above and other objects of the invention will become more apparent from the following description and accompanying drawings forming part of this application.

In the drawings:

Fig. 1 is a perspective view of one embodiment of the invention;

Fig. 2 is a bottom plan view of the embodiment shown in Fig. 1 with the base plate removed;

Fig. 3 is a top plan view of the base plate assembly;

Fig. 4 is a top plan view of the embodiment of the invention shown in Fig. 1 to illustrate the operation of the toy for moving trailers from a loading platform to a railroad flat car and vice versa;

Fig. 5 is a cross sectional view of Figs. 2, 3, and 4 taken along the line 5—5 thereof and illustrates certain steps in the operation of the toy;

Fig. 6 is a fragmentary section of a portion of Fig. 5 showing the use of the invention with a different type of standard model railroad track;

Fig. 7 is a cross sectional view of Figs. 2 and 5 taken along the lines 7—7 thereof;

Fig. 8 is a cross sectional view taken along the line 8—8 of Fig. 2;

Fig. 9 is a cross sectional view of Figs. 2 and 5 taken along the lines 9—9 thereof;

Figs. 10 and 11 are cross sectional views of Fig. 2 taken along the lines 10—10 and 11—11 thereof;

Fig. 12 is a side view of a trailer and a model flat car and illustrating certain details of the trailer to facilitate the alignment of the lifting mechanism with the trailer to place it on or remove it from the flat car;

Fig. 13 is a bottom view of the trailer of Fig. 12;

Figs. 14 and 15 are cross sectional views of Fig. 13 taken along the lines 14—14 and 15—15 thereof;

Fig. 16 is a fragmentary bottom view of the trailer

2

of Fig. 12 with the forward wheels in a retracted position; and

Fig. 17 is a cross sectional view of Fig. 16 taken along the lines 17—17 thereof.

5 Broadly the invention contemplates an improved toy which includes a loading platform having a boom pivotally mounted thereon including means for rotating the boom relative to the platform and means for lifting the boom vertically. The platform further includes means 10 for supporting vehicles to be lifted in predetermined positions relative to the boom so that the latter can be adjusted to engage and lift the vehicle or other object from the loading platform onto a carrier such as a railroad flat car or other similar vehicle arranged and coordinated with the loading platform. While the invention is illustrated herein in connection with the loading of model trailers onto model railroad flat cars, it is to be understood that the invention may be used for other similar purposes.

20 Referring now to the drawings, 10 denotes a raised platform having sets of depressions 11 and 12 adapted to receive the wheels of a trailer 13 or other similar vehicle. The loading platform further includes a pair of ramps 14 for moving the vehicles onto the platform surface 15 and a pair of controls in the form of a hand wheel 16 and a lever 17 for operation of the boom or lifting mechanism 18.

A simulated loading vehicle 18 is disposed centrally of the platform surface 15 and comprises a body 19 and 30 an outwardly extending boom 20. As will be shown the rotation of the wheel 16 will rotate the vehicle 18 and its boom 20 about a pivot so that the boom can be adjusted to engage cooperating elements on the bottom of the trailer 13. When this is accomplished movement of 35 the lever 17 is moved to raise the boom 20 and lift the trailer 13 whereupon the hand wheel 16 can again be operated to transport the trailer body onto a railroad flat car 21 or other similar vehicle. As shown in Fig. 1 one trailer 13 is in position on the flat car and the boom 20 is in position preparatory to picking up a second trailer 13 and transporting it into position on the flat car 21.

The structure of the vehicle 18 and the mechanism for operating it is shown more clearly in Figs. 2, 3, 4 and 5.

45 More specifically the top surface 15 of the platform 10 is provided with an opening 22 having a peripheral flange 23 to form a journal or bearing for a tubular shaft member 24. The lower end of the shaft member 24 carries a drive disc 25 having a ribbed or knurled edge portion 50 26. The drive disc is fixedly secured to the tubular shaft 24 and the latter carries on its upper side an angle bracket having a first leg 27 secured to the shaft 24 and a second leg 28 integral with the said first leg and extending upwardly therefrom. Rotation of the disc is 55 accomplished by a horizontal shaft 29 journaled in the wall 15' of the platform 10 and carrying on its outer end the wheel 16. In order to limit longitudinal displacement of the shaft 29 it is provided with a lock washer 30 which engages a cooperating groove on the shaft. 60 This groove is disposed just inside of the wall 15' so that the wheel 16 and the lock washer 30 limit translation of the shaft. The inner end of the shaft 29 is held in a horizontal position by a pair of downwardly extending guides 31 and carries on its inner end a friction sleeve 32 of rubber or other resilient material. This sleeve is held firmly against the knurled edge 26 of the drive disc 25 by a flat spring 33, the latter being pivoted on one end to a boss 34 extending downwardly from the underside of the housing (see Figs. 2 and 7) and then extends beneath a supporting rib 35 forming part of the platform 10. With this arrangement the friction sleeve 32 is held in firm engagement with the drive disc 25 so that

3

rotation of the hand wheel 16 will impart rotation to the angle bracket 27—28.

The boom 20 is fixedly secured to the top of a tubular lift column 36 that has an outside diameter somewhat smaller than the inside diameter of the hollow shaft 24 and the boom 20 is further provided with a pair of rearwardly extending fingers 37 that are adapted to engage the edges of the upwardly extending leg member 28 when the lift column 36 is in position in the shaft 24. In order to support and guide the lift column 36 an angle bracket 10 member 38 is secured to the leg 28 by a screw 39 or other suitable means with one leg 40 extending over and beyond the center of the tubular shaft member 24. A vertical shaft 41 is fixedly secured to the leg 40 of the bracket member 38, extends downwardly through the lift column 36 and engages a cooperating opening in the base plate 42 as will be observed in Fig. 5. With this arrangement it will be seen that the boom 20 is provided with firm support and can be reciprocated on the shaft 41. At the same time the fingers 37 of the boom 20 will impart rotation to the boom as the hand wheel 16 is operated.

In order to simulate realistically an actual mobile lifting mechanism, an ornamental body 19, simulating an automotive tractor, is secured to the leg 40 of the angle bracket 38 by means of a suitable screw 43 and rotates with the boom.

Vertical displacement of the boom 20 is accomplished by a lever generally denoted by the numeral 44. This lever is carried by the base plate 42 and has a pair of upwardly extending ears 45 pivoted to cooperating ears 46 formed on the base plate 42. In the instant embodiment of the invention the pivot comprises a pin 47 that extends through both sets of ears. The inner end 48 of the lever 44 is provided with a bifurcated end portion 49 that rests on the plate 42 and engages the bottom end of the lift column 36. The outer end 50 of the lever 44 is displaced upwardly and engages a lever 51 formed integrally with the control 17 and pivoted to a pair of downwardly extending bosses 52 on the underside of the platform 10 by means of a pivot pin 53. With the base plate 42 held in position on the platform by the engagement of a pair of ears 54 with cooperating openings 55 in the back side of the platform 10 and with the screws 56 extending through slots 57 in the platform 10 and engaging ears 58 on the base plate 42, movement of the lever 17 will operate the lever 44 and move the boom 20 to the raised position notwithstanding its angular position. In this way raising and lowering the boom 20 can be accomplished wholly independently of its rotation.

The instant embodiment of the invention is adapted to be used in connection with model railway equipment for the loading and unloading of trailers onto a flat car as shown in Fig. 1. In order to coordinate the platform 10 with conventional model railroad track generally denoted by the numeral 59, the base 42 is provided with a pair of brackets 60 pivoted to the base at 61 as shown in Fig. 3. These brackets each have a recess or cut out portion 62 adapted to receive the nearest wheel bearing rail 59' as shown in Fig. 5. In this way the track 59 is accurately located with respect to the platform 10. This arrangement facilitates the positioning of the toy relative to the track since the base 42 can be disengaged from the platform 10 and screwed to a mounting surface by means of mounting openings 63 with the track 59 engaged in the recesses 62.

The trailers 13 forming part of this invention each comprise a body 63' simulating the body of an actual van type trailer and a removable top or roof 64. In order to hold the top 64 in place it is provided with a pair of side flanges 65 and end tabs 66 and 67' which frictionally engage the inner surfaces of the wall of the body 63'. The rear wheels 67 of the trailer are supported by a pair of downwardly extending tabs 68 simulating the spring suspension of an actual vehicle and a piece of flexible tubing 69 extends transversely of the tab 68 and engages

cooperating openings therein. The wheels 67 are held by an axle 70 passing through the tubing 69 and cooperating openings in the wheels 67. The outer ends 71 of the axle 70 are upset to retain the wheels in position. In order to facilitate the assembly of the rear wheels it is preferable to fabricate them of a resilient material such as rubber, plastic, or the like so they can merely be forced over the upset portion 71 of the axle.

The front wheel or support assembly 72 for the trailer is pivotally mounted for retraction as in the case of an actual trailer. This front support assembly simulates a pair of wheels 73 and cooperating jacks 74 and these elements are formed integrally with a transverse cam member 75 and outwardly extending pivots or trunions 76. The assembly 72 is mounted on the trailer by engagement of the trunions 76 with cooperating recesses 77 formed on the underside of the trailer body and it is held in place by a leaf spring 78 secured to the body at 79 and having an S-shaped conformation 80 on its outer end for engagement with the cam member 75. With this arrangement the wheels cannot normally be moved forwardly but can be snapped to the rearward position as shown in Fig. 17 when the trailer is to be transported by a tractor. For present purposes the front support assembly 72 is normally retained in the extended position to support the trailer without the need for a tractor.

The spacing of the wheels 67 and 73 of the trailer are coordinated with the recesses 11 and 12 on the top surface 15 of the platform 10. The recesses 11 are made large enough to accommodate the rear wheel 67 and the edges of these recesses are tapered as shown in Fig. 11. The recesses 12 are of somewhat smaller dimensions to accommodate relatively small wheels 73 and the configuration of these recesses is shown in Fig. 10. Since all of the edges of the recesses are sloped the recesses will function to properly align the trailer on the platform surface 15 once it is placed in an approximate position.

In order to provide a firm engagement between the boom 20 and a trailer 13 when the latter is to be lifted, each trailer is provided with four openings or recesses 81 and the outer end of the boom 20 is provided with a pair of spaced bosses 82 having conical or tapered upper ends 82'. With this arrangement when the boom 20 is rotated in its lowered position beneath a trailer it is aligned with diagonally disposed recesses or openings 81. When the boom is raised the bosses 82 will enter these openings and firmly engage the trailer so that it can be transported by rotation of the hand wheel 16. Through the use of four recesses 81, the trailers 13 may be lifted from either position on the platform 10.

The transporting flat car 21 is of conventional construction but includes improved means for engaging the wheels of the trailer 13 to hold it on the surface thereof. More specifically, the flat car body 83 has an elongated central member 84 having a width corresponding to the width between the front and rear sets of truck wheels. The ends of the flat car are provided with transverse members 85 that extend beyond the front wheels 73 of the trailers and a transverse U-shaped member 86 bridges the central portion of the car body 83 to engage the rear wheels 67 of the trailer. Thus when the trailer is placed on the flat car as shown in Fig. 1 the trailer is held in place against both longitudinal and transverse movement and the flat car will hold two trailers 13 in back to back relationship.

Figs. 4 and 5 illustrate the operation of the toy. In Fig. 4 it will be observed that one trailer 13 is in place on the flat car 21 and a second is in position on the platform 15. To place the second or right hand trailer 70 on the flat car the boom 20 is rotated to a position wherein the bosses 82 are in line with the openings 81 in the bottom of the car 13. This is accomplished by rotation of the hand wheel 16. When proper alignment is obtained by the alignment of the edges of the boom 20 with markers 87 on one side or the other of the

trailer the lever 17 is actuated to raise the boom and lift the trailer. The hand wheel is then operated to move the boom over the flat car 21 whereupon the lever 17 is slowly returned to its original position to lower the trailer onto the flat car. Fig. 5 shows a fragmentary section of a trailer 13 denoted by the letter A in a raised position over the flat car 21 and in the lowered position B.

In conventional model railway equipment different heights of track are available with higher track being shown in Fig. 5 and the lower track shown in Fig. 6. With this invention and the novel and improved arrangement for supporting the boom 20 adequate elevation can be imparted to the boom 20 to accommodate both types of track and without modifying the accessory in any way.

From the foregoing description it will be observed that the aligned position of the flat car 21 is coordinated with the platform and the position of the vehicles 13 thereon so that the vehicles 13 whether on the flat car or platform are in the same angular positions relative to the pivotal axis of the boom. The platform and flat car positions of the vehicles 13 are actually separated by an angle of approximately 90° though it is apparent that other angular separations may be utilized.

While only one embodiment of the invention has been shown and described, it is apparent that modifications, changes and alterations may be made without departing from the true scope and spirit of the invention as defined by the appended claims.

What is claimed is:

1. A toy railroad accessory comprising a loading station, said loading station including a platform, vehicle positioning and holding means in the top face of said platform located in alignment with the wheel positions of a toy vehicle, a toy vehicle positioned on said platform and having wheels positioned in said vehicle positioning and holding means, a substantially vertical shaft rotatably mounted on said platform, said shaft being vertically reciprocable, a lifting device affixed to the upper end of said shaft, above said platform, said lifting device including a rigid outwardly extending lifting boom, hand operated means connected to said shaft to rotate said shaft, and hand operated means to reciprocate said shaft vertically to elevate and lower said lifting device, a track structure adjacent a side of said loading platform for positioning a flat car thereon, said lifting boom being movable through an arc intersecting the location

35

45

5

of said vehicle in a position to lift said vehicle and to a location extending beyond the edge of said platform and overlying said track.

2. A toy railroad accessory comprising a loading station, said loading station including a platform, at least four recesses defined in the top face of said platform in locations in alignment with the wheel positions of a toy vehicle, a toy vehicle positioned on said platform and having wheels positioned in said recesses, a substantially vertical shaft rotatably mounted on said platform, said shaft being vertically reciprocable, a lifting device affixed to the upper end of said shaft, above said platform, said lifting device including a rigid outwardly extending lifting boom, hand operated means connected to said shaft to rotate said shaft, and hand operated means to reciprocate said shaft vertically to elevate and lower said lifting device, a track structure adjacent a side of said loading platform for positioning a flat car thereon, said lifting boom being movable through an arc intersecting the location of said vehicle in a position to lift said vehicle and to a location extending beyond the edge of said platform and overlying said track.

3. A toy railroad accessory according to claim 2, wherein said platform is elevated and including an access ramp connected to said platform.

4. A toy railroad accessory according to claim 2, including an upstanding protuberance at the end of said boom, and a concavity formed at the underside of said vehicle complementary to said protuberance whereby the protuberance on said boom may be fitted into the cavity of said vehicle for lifting of said vehicle.
